UNITED STATES PATENT OFFICE.

ROWLAND S. NORTON, OF TROY, NEW YORK, ASSIGNOR TO GEORGE B. CLUETT, BROTHER & CO., OF SAME PLACE.

CUFF.

SPECIFICATION forming part of Letters Patent No. 242,025, dated May 24, 1881.

Application filed April 16, 1880. (Model.)

To all whom it may concern:

Be it known that I, ROWLAND S. NORTON, of the city of Troy, county of Rensselaer, and State of New York, have invented certain new and useful Improvements in the Mode of Manufacturing Cuffs, of which the following is a specification.

This invention relates to the manufacture of cuffs; and it consists in making a detachable cuff of an outer and inner face and the usual interlinings, all preferably of the same width, and in so placing them together for stitching wrong side out that the edges of the sides of the inner face will fold over the cut edges of the remaining parts, where they can be stitched down, if deemed advisable; and the object is to bring the closing side seams on the inner face of the cuff instead of at the edges; also, to produce a margin along the sides on the inner face, under which the raw edges of the interlinings may be concealed and prevented from raveling; also, to give increased thickness and rigidity to the edges of the cuff, and thereby to form a heavy beaded edge around the cuff.

In the drawings, Figure 1 is a plan view of the outer face of the cuff, showing the margins on the sides of the inner face for folding over the cut or raw edges of the remaining parts wrong side out. Fig. 2 is a similar view of the inner face of the cuff right side out, showing the cuff complete with beaded edge and with the edge seam on the inner face of the cuff. Fig. 3 is a perspective view of the four plies, showing the order of the same for sewing. Fig. 4 is a transverse sectional view of the cuff wrong side out. Fig. 5 is a similar sectional view of the cuff right side out before compressed.

Cuffs with beaded edges are not new, and cuffs with parts of different widths to make folds to form beaded edges are not new, and I make no claim to beaded edges, nor to cuffs any part of which is made wider than any other part.

To accomplish the object of my invention the inner face must be so placed on and stitched to the other parts of the cuff wrong side out that the edges of the inner face will project beyond the remaining edges, thereby "fulling

up" the outer face and interlinings, so that when 50 the parts are turned right side out the fullness or surplus of material in the outer face and interlinings must make up the deficiency in the width of the inner face, and thus bring the edge seams on the inner face of the cuff instead of 55 at the edges, thereby leaving a full and rounded edge. The outer face, A, as already stated and as seen in Fig. 1, is preferably of less width than the inner face, B, and the interlinings C are somewhat shorter than the outer and inner faces, 60 so that the folds on the side edges may be uniform, and I run or stitch the side edges together in such manner that the side edges of the inner face, B, will project far enough beyond the side edges of the remaining parts to make a margin 65 for folding over the cut side edges of the remaining parts. This margin is then folded over the cut side edges of the remaining parts, and, if preferred, is stitched down. These side edges are then run or stitched around with as 70 many rows of stitching and as far from the edges as the tastes of the manufacturer may require. I then turn the parts right side out. When turned right side out the fullness in the interlinings and outer face, produced by projecting the sides of the inner face, B, beyond the edges of the remaining parts, readily adjusts itself, so that the said side seams will 75 show on inner face of the cuff and not at the edges, and thus leave a clear rounded edge at 80 the sides. The edges, being necessarily doubled by turning the parts right side out, form a heavy beaded edge to be stitched down. The ends are then turned in and stitched down, and the entire cuff then stitched around to suit 85 the taste of the manufacturer.

By this mode of cutting and making a cuff a very handsome, serviceable, and merchantable cuff is produced with less labor and expense than the ordinary beaded cuff.

What I claim as my invention, and desire to secure by Letters Patent, is—

1. A cuff having its inner face stitched to the outer face and interlinings wrong side out in such position that the edges of the inner 95 face will project beyond the edges of the remaining parts and overlap them, in combination with the outer face and the interlinings

of a cuff, substantially as and for the purposes herein described.

2. A cuff cut of parts of unequal widths, and such parts superimposed upon each other wrong side out in such manner that the side edges of the inner face will project beyond the edges of the remaining parts, as herein described, so that when the parts are turned right side out the side edge seams will appear on the inner

side face of the cuff, substantially as herein described.

In witness whereof I have hereto set my hand this 15th day of March, 1880.

ROWLAND S. NORTON.
